STEROID PRODUCTION

Philip F. Beal III, Kalamazoo, and John A. Hogg, Portage Township, Kalamazoo County, Mich., assignors to The Upjohn Company, Kalamazoo, Mich., a corporation of Michigan

No Drawing. Application June 2, 1954,
Serial No. 434,071

8 Claims. (Cl. 260—239.55)

This invention relates to a novel process for the production of 3-cyclic ketals of alkyl 3-keto-11 β -hydroxy-4,17(20)-pregnadiene-21-oate.

It is an object of the present invention to provide a novel process for the production of a 3-cyclic ketal of alkyl 3 - keto - 11 β - hydroxy - 4,17(20) - pregnadiene-21-oate. Another object is the provision of a process for the conversion of a 3-cyclic ketal of alkyl 3,11-diketo-4,17(20)-pregnadiene-21-oate into a 3-cyclic ketal of 11 β ,21-dihydroxy-4,17(20)-pregnadiene-3-one. Still another object is the provision of a process for the conversion of alkyl 3,11-diketo-4,17(20)-pregnadiene-21-oate into 11 β ,21 - dihydroxy - 4,17(20) - pregnadiene - 3 - one. Other objects will be apparent to those skilled in the art to which this invention pertains.

The conversion of alkyl 3,11-diketo-4,17(20)-pregnadiene-21-oate to 11 β ,21-dihydroxy-4,17(20)-pregnadiene-3-one by reactions involving the process of the present invention may be represented by the following formulae:

2

wherein R is hydrogen or a lower-alkyl radical and n is the integer one or two.

According to the present invention, a 3-cyclic ketal of alkyl 3,11-diketo-4,17(20)-pregnadiene-21-oate (II) as defined herein is reduced with sodium borohydride to produce the corresponding 3-cyclic ketal of alkyl 3-keto-11 β -hydroxy-4,17(20)-pregnadiene-21-oate (III). The thus-produced 3-cyclic ketal of alkyl 3-keto-11 β -hydroxy-4,17(20)-pregnadiene-21-oate is converted to the corresponding 3-cyclic ketal of 11 β ,21-dihydroxy-4,17(20)-pregnadiene-21-oate (IV) by reduction with lithium aluminum hydride.

It is known that 11 β ,21-dihydroxy-4,17(20)-pregnadiene-3-one (V) can be produced from alkyl 3,11-diketo-4,17(20)-pregnadiene-21-oate (I) by the concurrent reduction of the 11-keto group and the 21-acid ester group with lithium aluminum hydride. This process has the disadvantage that the reduction of the 11-keto group with lithium aluminum hydride produces about twenty percent or more of the 11 α -hydroxy isomer. If the desired product is the 11 β -isomer, this production of 11 α -isomer is disadvantageous since it results in a corresponding reduction in yield of the 11 β -isomer. When a 3-cyclic ketal of 11 β ,21-dihydroxy-4,17(20)-pregnadiene-3-one (IV) is produced by the method of the present invention, i. e., reducing the 11-keto group of the starting 3-cyclic ketal of alkyl 3,11-diketo-4,17(20)-pregnadiene-21-oate (II) with sodium borohydride and the 21-acid ester group with lithium aluminum hydride, no significant amount of the 11 α -hydroxy isomer is obtained, and the yield of 11 β -hydroxy isomer is correspondingly higher. Since hydrocortisone is more readily prepared from the 11 β -isomer

than the 11α -isomer, this increase in yield of the 11β -isomer, when following the process of the present invention, is highly advantageous.

The thus-produced 3-cyclic ketal of $11\beta,21$ -dihydroxy-4,17(20)-pregnadiene-3-one (IV) is readily hydrolyzed under aqueous acid conditions to $11\beta,21$ -dihydroxy-4,17(20)-pregnadiene-3-one (V). $11\beta,21$ -dihydroxy-4,17(20)-pregnadiene-3-one can be converted to the physiologically active hydrocortisone acetate by acetylation of the 21-hydroxy group followed by oxygenation of the thus-produced 11β -hydroxy-21-acetoxyl-4,17(20)-pregnadiene-3-one with hydrogen peroxide and a small amount of osmium tetroxide in tertiary butyl alcohol, all as described more fully hereinafter.

The 3-cyclic ketal of alkyl 3,11-diketo-4,17(20)-pregnadiene-3-one (II) is readily prepared by the reaction of alkyl 3,11-diketo-4,17(20)-pregnadiene-21-oate (I) with an alkane-1,2-diol or alkane-1,3-diol, preferably ethylene glycol, in the presence of an acid catalyst, under ketalizing conditions, for example, as described in Preparation 3. Alkyl 3,11-diketo-4,17(20)-pregnadiene-21-oate (I) can be prepared by reacting 11-ketoprogesterone with ethyl oxalate in the presence of a molar equivalent of sodium ethoxide, followed, in turn, by bromination with about two molar equivalents of bromine and by reaction with a sodium alkoxide, ordinarily sodium methoxide or ethoxide, all as disclosed more fully in the preparations hereinafter.

In carrying out the process of the present invention, a 3-cyclic ketal of alkyl 3,11-diketo-4,17(20)-pregnadiene-21-oate (II), usually dissolved in a suitable solvent, e. g., an hydrous or aqueous isopropanol, methanol, ethanol, dioxane, tetrahydrofuran, or the like, is mixed with sodium borohydride, usually in an aqueous solution stabilized with alkali. An excess of sodium borohydride over the amount theoretically required may be employed and is ordinarily preferred. The reaction temperature is ordinarily somewhat above room temperature, e. g., between about 35 degrees centigrade and about fifty degrees centigrade, although temperatures between about zero degrees centigrade and about eighty degrees centigrade can be employed. Temperatures below about 35 degrees centigrade require fairly long reaction times to reach completion, whereas temperatures above about fifty degrees centigrade tend to cause decomposition of the sodium borohydride. Any excess sodium borohydride remaining at the end of the reaction can be decomposed with dilute acid or acetone.

The thus-produced 3-cyclic ketal of alkyl 3-keto- 11β -hydroxy-4,17(20)-pregnadiene-21-oate (III) can then be converted to a 3-cyclic ketal of 11β -21-dihydroxy-4,17(20)-pregnadiene-3-one (IV) by reduction with lithium aluminum hydride. The reduction can be performed in diethyl ether, tetrahydrofuran, benzene, Skellysolve B hexane hydrocarbons, or mixture of these, ordinarily at a temperature between about room temperature and the boiling point of the reaction mixture.

A preferred aspect of the present invention involves starting with a 3-cyclic ketal of alkyl 3,11-diketo-4,17(20)-pregnadiene-3-one and, without purification of the intermediate product, reducing the 11-keto group with sodium borohydride followed by reducing the 21-acid ester group with lithium aluminum hydride. The thus-reduced compound (IV) can then be hydrolyzed without purification to produce $11\beta,21$ -dihydroxy-4,17(20)-pregnadiene-3-one (V). For example, the 3-ethylene glycol ketal, or like ketal, of alkyl 3,11-diketo-4,17(20)-pregnadiene-21-oate (II) is preferably produced by the reaction of ethylene glycol or the like with an alkyl 3,11-diketo-4,17(20)-pregnadiene-21-oate (I) and is then reacted with sodium borohydride without purification. The thus-produced 3-ketal of alkyl 3-keto- 11β -hydroxy-4,17(20)-pregnadiene-21-oate (III) is then reduced with lithium aluminum hydride without isolation, to produce the 3-ketal of $11\beta,21$ -dihydroxy-4,17(20)-

pregnadiene-3-one (IV) which in turn can be hydrolyzed to produce $11\beta,21$ -dihydroxy-4,17(20)-pregnadiene-3-one (V). A convenient means of accomplishing this involves formation of II in benzene, distilling the benzene and replacing it with ethanol, adding the sodium borohydride to produce III, extracting III with ether and reacting it with an excess of lithium aluminum hydride, destroying the excess lithium aluminum hydride with water, acetone or ethanol, etc., distilling the ether, replacing the ether with acetone, and then acidifying the aqueous acetone solution with hydrochloric acid and hydrolyzing IV to produce V.

The following preparations and examples are illustrative of the products and process of the present invention but are not to be construed as limiting.

PREPARATION 1.—SODIUM ENOLATE OF 11-KETO-21-ETHOXYOXALYLPROGESTERONE

To a mixture of 3.4 milliliters of a 3.4 N methanolic sodium methoxide solution, 0.45 milliliter of absolute ethanol, and twenty milliliters of dry benzene, said mixture previously having been distilled until eight milliliters of distillate had been collected and then cooled, was added 2.3 milliliters of ethyl oxalate and a solution of 3.28 grams of 11-ketoprogesterone in 38 milliliters of dry benzene. The solution became turbid and a yellow precipitate formed. The reaction mixture was stirred for ninety minutes, 55 milliliters of ether was then added thereto, and stirring was continued for sixty minutes, whereafter a 130-milliliter portion of ether was added thereto. The thus-formed yellow precipitate of the sodium enolate of 11-keto-21-ethoxyoxalylprogesterone was filtered, washed with several fifty-milliliter portions of ether, and after drying found to weigh 3.65 grams. The ether wash contained 0.54 gram of unreacted 11-ketoprogesterone. The yield of the sodium enolate of 11-keto-21-ethoxyoxalylprogesterone was 81 percent of the theoretical or practically quantitative calculated on the reacted 11-ketoprogesterone. The presence of a sodium enolate was verified by the extreme solubility of the product in water and by a positive ferric chloride test for enols as exhibited by the formation of a bright red color when the product was dissolved in alcoholic and aqueous ferric chloride solutions.

PREPARATION 2.—METHYL 3,11-DIKETO-4,17(20)-PREGNADIENE-21-OATE

To a stirred solution of 4.50 grams (0.01 mole of the sodium enolate of 11-keto-21-ethoxyoxalylprogesterone and two grams of potassium acetate in 150 milliliters of methanol was added dropwise 3.09 grams (1.00 ml.; 0.0193 mole) of bromine. When the addition was complete, 3.24 grams (0.06 mole) of sodium methoxide in forty milliliters of methanol was added thereto, whereafter the whole was maintained at about 25 degrees centigrade for sixteen hours. The reaction mixture was then mixed with a large volume of water and the whole was extracted successively with one portion of benzene and two portions of methylene chloride. The combined extracts were dried over anhydrous sodium sulfate and the solvent was then removed therefrom by distillation. The residue was dissolved in 100 milliliters of methylene chloride and chromatographed over and eluted from 150 grams of Florisil synthetic magnesium silicate with methylene chloride containing increasing amounts of acetone. The methylene chloride plus five percent acetone eluates contained 1.2 grams of 3,11-diketo-4,17(20)-pregnadiene-21-oic acid methyl ester, melting at 155 to 188 degrees centigrade. Crystallization of these crystals from a mixture of acetone plus Skellysolve B hexane hydrocarbons gave crystals melting at 207 to 212 degrees centigrade.

Similarly, other alkyl esters of 3,11-diketo-4,17(20)-pregnadiene-21-oic acid such as, for example, the ethyl ester, the propyl, butyl, amyl, hexyl, heptyl, octyl, or like ester, are prepared by reacting the sodium enolate

of 11-keto-21-ethoxyoxalylprogesterone with a sodium or potassium alkoxide wherein the alkyl group of the alkoxide is the same as the alkyl ester group of the desired steroid product.

PREPARATION 3.—3-ETHYLENE GLYCOL KETAL OF METHYL 3,11-DIKETO-4,17(20)-PREGNADIENE-21-OATE

To a solution of 1.5 grams (0.0042 mole) of methyl 3,11-diketo-4,17(20)-pregnadiene-21-oate dissolved in 150 milliliters of benzene was added 7.5 milliliters of ethylene glycol and 0.150 gram of para-toluenesulfonic acid and the whole was then heated with stirring at the reflux temperature of the reaction mixture for 5.5 hours. The cooled reaction mixture was washed with 100 milliliters of a one percent aqueous sodium bicarbonate solution. The benzene layer was then poured on a column of 150 grams of Florisil synthetic magnesium silicate. The column was developed with 100-milliliter portions of solvents of the following composition and order: eight portions of methylene chloride and three portions of methylene chloride plus four percent acetone. The methylene chloride eluates contained 1.08 grams of the 3-ethylene glycol ketal of methyl 3,11-diketo-4,17(20)-pregnadiene-21-oate, which upon recrystallization from a mixture of ethyl acetate and Skellysolve B hexane hydrocarbons melted at 188 to 190 degrees centigrade and had the analysis given below. The methylene chloride plus four percent acetone eluates contained 0.390 gram of pure starting methyl 3,11-diketo-4,17(20)-pregnadiene-21-oate. The yield of product was 87 percent of the theoretical calculated on the amount of starting steroid which reacted.

Analysis.—Calculated for $C_{24}H_{32}O_5$: C, 71.94; H, 8.05. Found: C, 71.90; H, 7.95.

Similarly, the 3-ethylene glycol ketals of other alkyl esters of 3,11-diketo-4,17(20)-pregnadiene-21-oic acid such as, for example, the ethyl ester, the propyl, butyl, amyl, hexyl, heptyl, octyl, or like esters, are prepared by reacting the selected alkyl ester of 3,11-diketo-4,17(20)-pregnadiene-21-oic acid with ethylene glycol according to the method described in Preparation 3 in the presence of an acid catalyst such as, for example, anhydrous hydrogen chloride, benzenesulfonic acid, para-toluenesulfonic acid, or the like.

In the same manner as described above, reacting methyl 3,11-diketo-4,17(20)-pregnadiene-21-oate with trimethylene glycol in the presence of an acid catalyst is productive of the 3-trimethylene glycol ketal of methyl 3,11-diketo-4,17(20)-pregnadiene-21-oate.

Similarly, other 3-ketals of this and other esters of 3,11-diketo-4,17(20)-pregnadiene-21-oic acid are produced by the reaction of the selected ester of the above-described steroid acid, especially the methyl, ethyl, propyl, butyl, amyl, hexyl, heptyl, or octyl ester, with a glycol such as, for example, ethylene glycol, propylene glycol, trimethylene glycol, an alkyl substituted ethylene glycol, propylene glycol, or trimethylene glycol, or the like, in the presence of an acid catalyst, such as, for example, para-toluenesulfonic acid, hydrogen chloride, sulfuric acid, or the like.

Example 1.—3-ethylene glycol ketal of methyl 3-keto-11 β -hydroxy-4,17(20)-pregnadiene-21-oate

A mixture of five grams (0.014 mole) of methyl 3,11-diketo-4,17(20)-pregnadiene-21-oate, twenty milliliters of ethylene glycol and 0.3 gram of para-toluenesulfonic acid in 150 milliliters of benzene was refluxed with vigorous stirring for five hours. The mixture was cooled and washed with twenty milliliters of a saturated aqueous solution of sodium bicarbonate and then with water. The sodium bicarbonate and aqueous washes were extracted with benzene which was added to the washed benzene. The combined benzene solutions were dried with sodium sulfate and the benzene distilled therefrom to leave a residue consisting essentially of the 3-ethyl-

ene glycol ketal of methyl 3,11-diketo-4,17(20)-pregnadiene-21-oate.

The thus-produced 3-ethylene glycol ketal of methyl 3,11-diketo-4,17(20)-pregnadiene-21-oate was dissolved in 100 milliliters of isopropyl alcohol and a solution of two grams of sodium borohydride in twenty milliliters of an 0.1 N solution of aqueous sodium hydroxide was added thereto. The solution was stirred for four days at 37 degrees centigrade, at the end of which time no sodium borohydride remained. The isopropyl alcohol was distilled at reduced pressure and the residue extracted with two 125-milliliter portions of benzene which were combined and reduced in volume to about one-half by distillation at reduced pressure. The resulting benzene solution was chromatographed over 300 grams of Florisil synthetic magnesium silicate with Skellysolve B hexane hydrocarbons containing increasing amounts of acetone. The eluate fractions consisting of Skellysolve B plus five percent acetone contained 4.25 grams, a yield of 85 percent of the theoretical, of the 3-ethylene glycol ketal of methyl 3-keto-11 β -hydroxy-4,17(20)-pregnadiene-21-oate which, after recrystallization from ethyl acetate, melted at 167 to 169 degrees centigrade and had the analysis given below.

Analysis.—Calculated for $C_{24}H_{34}O_5$: C, 71.61; H, 8.51. Found: C, 71.65; H, 8.78.

Similarly, other 3-cyclic ketals of alkyl 3-keto-11 β -hydroxy-4,17(20)-pregnadiene-21-oates are prepared by reaction of sodium borohydride with a 3-cyclic ketal of an alkyl 3,11-diketo-4,17(20)-pregnadiene-21-oate, especially those described in Preparation 3, wherein the cyclic ketal group and alkyl ester group correspond to the desired cyclic ketal group and an alkyl ester group of the reaction product. Starting steroids for this reaction include 3-cyclic ketals of alkyl 3,11-diketo-4,17(20)-pregnadiene-21-oates wherein the cyclic ketal group is, for example, the ethylene glycol ketal, the propylene or trimethylene glycol ketal, or the cyclic ketals derived from butane-1,2-diol, butane-1,3-diol, butane-2,3-diol, pentane-1,2-diol, hexane-1,2-diol, heptane-1,2-diol, octane-1,2-diol, and others, and wherein the alkyl group is, for example, methyl, ethyl, propyl, isopropyl, amyl, isoamyl, sec-amyl, hexyl, heptyl, octyl and the like.

Example 2.—3-ethylene glycol ketal of 11 β ,21-dihydroxy-4,17(20)-pregnadiene-3-one

A solution of 1.62 grams of the 3-ethylene glycol ketal of methyl 3-keto-11 β -hydroxy-4,17(20)-pregnadiene-21-oate, prepared in the manner described in Example 1, in seventy milliliters of benzene was added dropwise to a stirred mixture of 1.50 grams of lithium aluminum hydride and fifty milliliters of anhydrous ether. When addition was complete, the reaction mixture was refluxed for one-half hour whereafter the mixture was cooled to room temperature. Fifty milliliters of water was then cautiously added to the stirred reaction mixture to decompose the excess lithium aluminum hydride, followed by 200 milliliters of methylene chloride. The whole was then centrifuged to facilitate separation of the organic and aqueous phases. The organic phase was separated, the solvent distilled and the white crystalline distillation residue was crystallized from a mixture of ethyl acetate and Skellysolve B hexane hydrocarbons to yield crystalline 3-ethylene glycol ketal of 11 β ,21-dihydroxy-4,17(20)-pregnadiene-3-one in two crops. The first crop, the analysis of which is given below, melted at 191 to 194 degrees centigrade and the second at 172 to 180 degrees centigrade.

Analysis.—Calculated for $C_{23}H_{34}O_4$: C, 73.76; H, 9.15. Found: C, 73.87; H, 9.22.

In the same manner as described above, the 3-propylene glycol ketal of 11 β ,21-dihydroxy-4,17(20)-pregnadiene-3-one is prepared by reacting with lithium aluminum hydride in ether the 3-propylene glycol ketal of an alkyl ester of 3-keto-11 β -hydroxy-4,17(20)-pregnadiene-21-oic acid, prepared as given in Example 1.

Similarly, other 3-ketals of $11\beta,21$ -dihydroxy-4,17(20)-pregnadiene-3-one are prepared by reacting other 3-ketals of alkyl 3-keto- 11β -hydroxy-4,17(20)-pregnadiene-21-oate, e. g., the ethyl, propyl, isopropyl, butyl, amyl, hexyl, heptyl, or octyl ester of 3-ethylene glycol ketal of 3-keto- 11β -hydroxy-4,17(20)-pregnadiene-21-oic acid, the 3-propylene glycol, propane- α -diol, butane-1,2-diol, butane-1,3-diol, pentane-1,2-diol, pentane-2,3-diol, hexane-1,2-diol, heptane-1,3-diol, octane-1,2-diol or like 3-cyclic ketal of methyl 3-keto- 11β -hydroxy-4,17(20)-pregnadiene-21-oate, with lithium aluminum hydride in ether, dioxane, tetrahydrofuran, or other suitable solvent.

Example 3.— $11\beta,21$ -dihydroxy-4,17(20)-pregnadiene-3-one

One gram of the 3-ethylene glycol ketal of methyl 3-keto- 11β -hydroxy-4,17(20)-pregnadiene-21-oate, prepared according to the method described in Example 1, but not purified, was dissolved in 25 milliliters of benzene and 0.25 gram of lithium aluminum hydride dissolved in 25 milliliters of absolute ether was slowly added thereto. The resulting mixture was stirred for about eighteen hours and then decomposed by the addition of water. The decomposed mixture was filtered, the filter cake being washed thoroughly with ethyl acetate and ether. The filtrate was evaporated and the residue dissolved in forty milliliters of acetone. To this solution was added ten milliliters of water and eight drops of concentrated sulfuric acid and the mixture allowed to stand for about eighteen hours. The solution was neutralized with sodium bicarbonate and then evaporated at room temperature. The reaction product was separated from the inorganic salts by extraction with ethyl acetate which was then evaporated. The residue was recrystallized from a mixture of ethyl acetate and Skellysolve B hexane hydrocarbons to give a first crop of 440 milligrams, a yield of 53.6 percent of the theoretical, of $11\beta,21$ -dihydroxy-4,17(20)-pregnadiene-3-one, melting at 182 to 186 degrees centigrade and a second crop of 160 milligrams.

An alternative procedure for the hydrolysis step involving the hydrolysis of the isolated 3-ethylene glycol of $11\beta,21$ -dihydroxy-4,17(20)-pregnadiene-3-one is shown below.

A solution of 0.572 gram (0.0015 mole) of the 3-ethylene glycol ketal of $11\beta,21$ -dihydroxy-4,17(20)-pregnadiene-3-one in forty milliliters of acetone was diluted with water to a volume of fifty milliliters and eight drops of concentrated sulfuric acid was then added thereto, whereafter the reaction mixture was kept at room temperature for 24 hours. The reaction mixture was then made alkaline by the addition of a saturated aqueous sodium bicarbonate solution and the acetone was then evaporated from the mixture. Methylene chloride and more water were then added, the methylene chloride layer removed, and the solvent distilled therefrom. The residue, after drying in vacuo, consisted of the theoretical 0.518 gram of $11\beta,21$ -dihydroxy-4,17(20)-pregnadiene-3-one.

In the same manner as described in Example 3, $11\beta,21$ -dihydroxy-4,17(20)-pregnadiene-3-one is prepared by contacting other 3-ketals of $11\beta,21$ -dihydroxy-4,17(20)-pregnadiene-3-one, especially the 3-ketals described in the preparations and examples hereinbefore, with a hydrolyzing agent such as, for example, dilute hydrochloric acid, sulfuric acid, or the like.

The conversion of $11\beta,21$ -dihydroxy-4,17(20)-pregnadiene-3-one into the physiologically active hydrocortisone acetone is shown below.

11β -hydroxy-21-acetoxy-4,17(20)-pregnadiene-3-one

A solution of 0.518 gram of $11\beta,21$ -dihydroxy-4,17(20)-pregnadiene-3-one in five milliliters of pyridine was mixed with two milliliters of acetic anhydride and the whole was then maintained at room temperature for seventeen

hours whereafter crushed ice was added thereto. The precipitated 11β -hydroxy-21-acetoxy-4,17(20)-pregnadiene-3-one was filtered therefrom, dissolved in benzene and then chromatographed over a column of 75 grams of Florisil synthetic magnesium silicate. The column was developed with 75-milliliter portions of solvents of the following composition and order: benzene, three portions each of Skellysolve B hexane hydrocarbons plus one percent acetone, Skellysolve B plus five percent acetone, Skellysolve B plus ten percent acetone; Skellysolve B plus fifteen percent acetone; Skellysolve B plus twenty percent acetone, and finally, two portions of acetone. The eluate fractions containing ten percent and fifteen percent acetone, respectively, were combined, the solvent removed therefrom, and the crystalline residue was crystallized from a mixture of ethyl acetate and Skellysolve B to yield as the first crop 0.253 gram, a yield of 45 percent of the theoretical, of 11β -hydroxy-21-acetoxy-4,17(20)-pregnadiene-3-one melting at 183 to 186 degrees centigrade.

Analysis.—Calculated for $C_{23}H_{32}O_4$: C, 74.16; H, 8.66. Found: C, 74.18; H, 8.45; C, 73.95; H, 8.74.

$11\beta,17\alpha,21$ -trihydroxy-4-pregnene-3-one (Kendall's Compound F)

To a stirred suspension of 0.124 gram (0.00033 mole) of 11β -hydroxy-21-acetoxy-4,17(20)-pregnadiene-3-one in two milliliters of tertiary butyl alcohol was added 0.26 milliliter of a 2.6 molar solution of hydrogen peroxide in tertiary alcohol and 0.30 milliliter of a solution of 1.00 gram of osmium tetroxide in 100 milliliters of tertiary butyl alcohol. An additional 0.50 milliliter of the above-described osmium tetroxide solution was added to the reaction mixture during the next thirty hours. After the first four hours of reaction time the reaction mixture darkened and became homogeneous. The reaction mixture was stirred and maintained at room temperature for an additional 84 hours, whereafter water and methylene chloride were added thereto. The whole was distilled at reduced pressure to remove the organic solvents and the product was extracted from the residue with methylene chloride, whereafter the extract was freed of solvent by evaporation. The residue, after dissolving in a mixture of five milliliters of methanol and one milliliter of a solution of 0.30 gram of sodium sulfite in five milliliters of water, was heated on a steam bath for thirty minutes. The $11\beta,17\alpha,21$ -dihydroxy-4-pregnene-3,20-dione was separated therefrom by extraction with methylene chloride, which was thereafter removed by distillation in vacuo. The 0.101 gram of residue consisted of about fifty percent of the desired $11\beta,17\alpha,21$ -trihydroxy-4-pregnene-3,20-dione (Kendall's Compound F).

It is to be understood that this invention is not to be limited to the exact details of operation or exact compounds shown and described as obvious modifications and equivalents will be apparent to one skilled in the art and the invention is therefore to be limited only by the scope of the appended claims.

We claim:

1. The process which comprises: reducing with sodium borohydride a 3-cyclic ketal of alkyl 3,11-diketo-4,17(20)-pregnadiene-21-oate represented by the following formula:

wherein R is selected from the group consisting of hydrogen and lower-alkyl groups and n is an integer from one to two, to produce the corresponding 3-cyclic ketal of alkyl 3-keto-11 β -hydroxy - 4,17(20) - pregnadiene-21-oate.

2. The process of claim 1 wherein R is hydrogen and n is the integer one.

3. The process of claim 1 wherein R is hydrogen and n is the integer two.

4. The process of claim 1 wherein R is hydrogen, n is 10 and the integer one and the alkyl group is methyl.

5. The process of claim 1 wherein R is hydrogen, n is the integer one, the alkyl group is methyl, the reaction solvent is an aqueous alkali containing lower-alkanol and the reaction temperature is between about 35 and 15 about fifty degrees centigrade.

6. The process which comprises the steps of (1) reducing with sodium borohydride a 3-cyclic ketal of alkyl 3,11-diketo - 4,17(20) - pregnadiene-21-oate represented by the following formula:

25

30

wherein R is selected from the group consisting of hydrogen and lower-alkyl groups and n is an integer from one to two, to produce the corresponding 3-cyclic ketal of alkyl 3-keto-11 β -hydroxy - 4,17(20) - pregnadiene-21-oate, and (2) reducing the thus-produced 3-cyclic ketal of alkyl 3-keto-11 β -hydroxy - 4,17(20) - pregnadiene-21-oate with lithium aluminum hydride to produce the corresponding 3-cyclic ketal of 11 β ,21-dihydroxy-4,17(20)-pregnadiene-3-one.

7. The process of claim 6 wherein R is hydrogen and n is the integer one.

8. The process of claim 6 wherein R is hydrogen, n is the integer one and the alkyl group is methyl.
